(57) **CLAIM**

The ornamental design for a chain called venetian rope, substantially as shown and described.

DESCRIPTION

The chain may be used to construct necklaces, rings, ear rings other jewelry items that can be constructed from chain.

FIG. 1 is a front elevational view of an arbitrary length of the ornamental chain showing the new design;

FIG. 2 is a front view of an embodiment of a segment of the ornamental chain showing the new design, the segment having open ends for receiving additional links;

FIG. 3 is a side view of the segment of ornamental chain shown in FIG. 2;

FIG. 4 is a front elevational view of a single link used to create the ornamental chain of FIG. 2; and,

FIG. 5 is a front elevational view of another embodiment a single link used to create the ornamental chain of FIG. 2, wherein the link is constructed from a segmented portion and a non-segmented portion, and wherein the non-segmented portion is not visible when placed into the ornamental chain.
